RECESS TOOL FOR TRENAILS AND DOWELS

Edwin C. Swanson and Carl O. Rudeen, Rockford, Ill., assignors to Greenlee Bros. & Co., Rockford, Ill., a corporation of Illinois

Application July 12, 1943, Serial No. 494,332

4 Claims. (Cl. 145—124)

This invention relates to a tool for imparting a desired shape to the hole adapted to receive a trenail or dowel, and has special reference to a tool adapted to flare the walls of the opening adjacent its ends for the purpose of permitting the ends of the trenail or dowel to be expanded to lock the parts in position.

The tool herein shown and described is intended for use in the wood-working art in which elements of a wooden structure are secured together by wooden pins, dowels and the like. This type of construction is common in the boat building art in which the pins are referred to as trenails. According to one system now in use the trenails are so arranged that they may be expanded at their ends so as to prevent the parts from becoming dislodged even where the glue holding the parts together has completely disintegrated, and an important object of this invention is the provision of a simple tool for recessing or flaring the ends of the bore in which the trenail is placed to provide space in the bore for the expansion of the trenail.

A further object of the invention is the provision of a tool adapted to flare the bore simultaneously at both ends thereof in a single operation of the tool.

A still further object of the invention is the provision of a recessing tool in which the cutter is normally retained wholly within the confines of a cylinder defined by the outer walls of the holder and is projected outwardly in response to pressure applied to the holder so that the cutter is progressively forced outwardly as the tool is rotated to cut an annular recess adjacent the end of the hole.

Other objects and advantages will appear from the following description and the accompanying drawing, in which—

Figure 1 is a side elevation partly in section showing the tool disposed in a bore of a work piece;

Fig. 2 is a fragmentary view showing partially in section the arrangement of the parts at the lower end of the tool prior to projection of the cutter;

Fig. 3 is a view similar to Fig. 2 showing the position of the parts when the cutter is projected;

Fig. 4 is a side elevation of the tool showing an intermediate step in the flaring of both ends of the bore;

Fig. 5 is a view similar to Fig. 4 showing the final step in the flaring of the two ends of the bore;

Fig. 6 is a front elevation of the lower end of the cutter holder;

Fig. 7 is a front elevation of the lower cutter;

Fig. 8 is a lower end view of the lower cutter, and

Figs. 9 through 11 are sectional views showing the manner in which the trenail is disposed in the work piece.

One method now being used for making dowel connections between elements of wooden structures is shown in Figs. 9 through 11. In Fig. 9 the letter A designates a wooden structural element attached to the surface of an element B by means of a trenail C. This trenail consists of a dowel in which an annular groove D is placed in the end of the dowel. This is inserted into a bore E which is flared as shown at F adjacent its bottom, a tapered tubular wedge G being positioned with its narrowest edge barely inserted in the groove D. Thereafter the parts are forced together forcing the wedge into the position shown in Fig. 9 and thus flaring or expanding the inner end of the dowel so that it can be no longer removed from the bore. In Fig. 11 two elements of wood H and J are fastened by a trenail K having ends L and M expanded in the manner shown in detail in Fig. 9. The present invention is directed to a tool adapted for insertion in a previously bored hole for the purpose of recessing or flaring the bores to permit the expansion of the ends of the trenail as shown at F, L and M in Figs. 9 through 11.

The present embodiment of the invention contemplates the provision of a shank designated generally by the numeral 15 adapted for reception in the chuck of a power driven tool such as a drill press or the chuck of a drill stock, as the case may be. Integral with the shank 15 is a shaft 16 of suitable length depending upon the nature of the particular work, the lower end of the shaft 16 having a cutter support 17 preferably cylindrical in shape and integral with the shaft. The lower end of the cutter support is beveled off diagonally as shown at 18 and is provided with a longitudinal slot 19, opposite sides of which are provided with grooves or ways 21 and 22 parallel with the beveled end 18 as best shown in Figs. 2 and 6. The cutter support also has a longitudinal bore 23 opening into the slot 19 with which is received a sliding plug 24 normally urged outward by means of a coil spring 25.

Disposed within the slot 19 is a bottom cutter indicated generally by the numeral 26, the cutter having a cylindrical lower end portion 27, a flat end surface 27a and a laterally disposed cut-

ting lip or edge 28 extending from the bottom upwardly as shown best in Figs. 2 and 3. The cutter has spaced cam shoulders 29 and 31 on opposite sides thereof adapted to abut against the sloping lower end 18 of the holder and disposed at an angle corresponding to that of the beveled end 18, the opposed sides of the cutter above the shoulders 29 and 31 being flat and disposed in parallel planes for snug reception between the side walls of the slot 19, these surfaces being indicated by the numerals 32 and 33. Disposed on the surfaces 32 and 33 are ribs 34 and 35 complementary to the ways 21 and 22 and adapted for reception therein, the ribs being parallel to and spaced from the shoulders 29 and 31. The upper end of the cutter has a recess 36 adapted for reception of a finger 37 integral with the sliding plug 24. It will be seen that when the plug 24 is moved upward the cutter may be slid diagonally into the slot 19 with the surfaces 32 and 33 fitting snugly against the walls of the slot and the ribs 34 and 35 disposed in the ways 21 and 22 in the manner shown in Figs. 2 and 3. The finger 37 then seats in the recess 36. The length of the cutter is preferably slightly greater than the maximum length of the slot 19 but the spring 25 urges the plug 24 against the cutter and normally moves the cutter downward and laterally into the position shown in Fig. 2, the extent of this movement being limited by contact of the finger 37 with the end of the recess 36 as shown at 38 forming a stop for this movement of the cutter. This causes the lower end of the cutter to project out beyond the end of the holder. The dimension of the cutter parallel to the faces 32 and 33 is somewhat smaller than the diameter of the holder and the cutter edge 28 projects out from the face of the cutter a distance equal to the amount of flare or recess desired in the bottom of the work piece opening which in turn corresponds to the flare to be placed on the trenail. Thus it will be seen that when the shank 15, the shaft 16 and the holder 17 are forced downwardly so that the lower end of the cutter is forced against the bottom of the opening as shown in Fig. 2 and with the tool rotating, the tool is forced on down from the position shown in Fig. 2, the cutter is forced radially outward by interaction of the ribs 34 and 35, and the ways 21 and 22, bringing the cutter edge 28 against the work, this movement continuing until the cutter abuts against the surface of the bore in the area above the cutting edge and until the finger 37 comes into engagement with the opposite end 39 of the recess 36 and which forms the other stop for the cutter, the parts then assuming the position shown in Fig. 3. When the tool is withdrawn from the bore, the spring 25 together with the sloping edge of the cutting edge 28 act to move the cutter back within the confines of a cylinder formed by the outer walls of the holder, or in other words, into the position shown in Fig. 2 so that the tool may be withdrawn from the bore.

For certain types of dowel connections it is possible to recess or flare both ends of the bore in a single operation, as, for example, the type of connection shown in Figs. 4, 5 and 11. For this purpose a second or upper cutter designated by the numeral 41 is provided. This cutter comprises a collar 42 disposed to fit snugly on the shaft 16 in such manner as to be capable of adjustment longitudinally with respect to the shaft, the collar having a set screw 43 for the purpose of definitely locating the cutter on the shaft.

The collar has a flange 44 provided with a cutting edge 45, the flange and cutting edge having the slope required to provide the necessary flare at the end of the hole. In service the cutter 41 is adjusted on the shaft 16 in such relationship with the lower cutter 26 that when the tool is forced down into the bore, the two recesses will be produced simultaneously as shown in Figs. 4 and 5, the cutting edge 41 first engaging the outer end of the bore as shown in Fig. 4 as the tool moves into the work and thereafter continuing its cutting stroke until the parts reach the position shown in Fig. 5.

It will be seen that the tool provides a novel means by which in a single operation the bottom of a trenail bore may be flared for the expansion of the trenail as it is inserted into the work, and likewise provides means in which both of the flares can be produced in a single unitary operation. The cutter holder 17 is made of such size as to snugly fit the bore and consequently the bore serves as a guide for the tool to insert the recess being produced uniformly about the axis of the bore. Furthermore, the tool is so arranged that in each instance the recess is cut to a definite and prescribed depth in the work so as to cause the trenail when inserted and expanded to snugly fit the recessed bore.

We claim:

1. A recessing tool for trenails and the like comprising a cutter holder shaped for reception in a bore of a work piece in guiding relation therewith and having a transverse slot in one end thereof, a cutter disposed in said slot of smaller transverse dimensions than said holder, said cutter projecting from the end of the holder and having a radially disposed cutting edge on one side thereof in sloping relation with the longitudinal axis of the tool, cooperative ribs and ways disposed between opposite sides of said cutter and the walls of said slot inclined with respect to the longitudinal axis of said holder and cutter, said ribs and ways being positioned and shaped for movement of the cutter with respect to the holder between a lower position in which the cutter projects from the end of said holder and an upper position in which said cutting edge projects from the side of said holder, a spring enclosed within the holder acting on the cutter to urge the same to said lower position, the cutter having lateral movement with respect thereto, a shaft on the opposite end of said holder for rotating the tool and for pressing the same against the bottom of the bore to move the cutter laterally outwardly with respect to the bore and thereby cut an annular recess at the bottom of the bore and stop means for limiting the extent of the lateral movement in each direction.

2. A recessing tool for trenails and the like comprising a cutter holder of cylindrical shape for reception into the bore of a work piece in guiding relationship therewith, said holder having a transverse slot in the lower end thereof providing a bottom wall and spaced parallel side walls, a cutter of smaller transverse dimensions than said holder disposed in said slot, said cutter having a substantially flat bottom end and a sloping radially disposed cutting edge on one side thereof, cooperative ribs and ways disposed between said cutter and said side walls inclined with respect to the longitudinal axis of said holder and positioned and shaped for movement of the cutter on the holder between a lower position in which said cutter projects from the end of said holder and an upper position in which said cut-

ting edge projects from the side of said holder, a spring pressed sliding plunger disposed in said holder at the bottom of said slot bearing against the upper end of said cutter to normally urge the same to said lower position, said cutter having stops positioned to engage said plunger to define said upper and lower positions, and a shaft on said holder adapted for reception in a chuck for rotating the tool and moving the same longitudinally into the bore and against the bottom thereof to move the cutter to said upper position and thereby cut an annular recess at the bottom of the bore.

3. A recessing tool for trenails and the like comprising a cutter holder of cylindrical shape for snug reception into the bore of a work piece in guiding relationship therewith, said holder having a lower end inclined with respect to the longitudinal centerline thereof and a transverse slot bisecting said inclined lower end and extending longitudinally of the holder to provide spaced parallel side walls and spaced inclined end segments on the holder, a cutter of smaller transverse dimensions than said holder supported in the lower end of the latter and in one position projecting therefrom with all parts thereof disposed within a plane defined by the outer surface of the holder, the cutter having a peripherally disposed cutting edge, a substantially flat end surface for abutment against the bottom of the bore and an opposite end spaced from the bottom of said slot in the aforesaid position, a lower end portion approaching the cylindrical in shape, and an upper portion of lesser thickness than the diameter of said lower portion having parallel side surfaces for snug reception in said slot, the junction between said portions comprising inclined cam shoulders complementary to said end segments, cooperative ribs and ways disposed between said side surfaces and said side walls, inclined with respect to the longitudinal axis of said holder and cooperative with said end segments and said cam shoulders to move the cutter laterally when the holder is forced down with the end surface of the cutter

5 the bottom of the bore to cause the cutting edge to project from the plane of the holder and to cause said opposite end to approach the bottom of said slot, and spring means disposed within the holder acting against said opposite end and moving the cutter from the second to the first position.

4. A recessing tool for trenails and the like comprising a cutter holder of cylindrical shape for snug reception into the bore of a work piece in guiding relationship therewith, said holder having a lower end inclined with respect to the longitudinal centerline thereof and a transverse slot bisecting said inclined lower end and extending 10 longitudinally of the holder to provide spaced parallel side walls and spaced inclined end segments on the holder, a cutter of smaller transverse dimensions than said holder supported in the lower end of the latter and projecting therefrom, the cutter having a substantially flat end surface for abutment against the bottom of the bore, a lower end portion approaching the cylindrical in shape, and an upper portion of lesser thickness than the diameter of said lower portion 15 having parallel side surfaces for snug reception in said slot, the junction between said portions comprising inclined cam shoulders complementary to said end segments, cooperative ribs and ways disposed between said side surfaces and said side walls, inclined with respect to the longitudinal axis of said holder and cooperative with said end segments and said cam shoulders to move the cutter laterally when the holder is forced down with the end surface of the cutter 20
